Appended hereto is a file copy of a specification and drawings of an invention, which invention is described in and claimed in and by the following specification and drawings.

UNITED STATES PATENT OFFICE

LOUIS STIENNEN, OF NEW HAVEN, CONNECTICUT, ASSIGNOR TO WINCHESTER REPEATING ARMS COMPANY, OF NEW HAVEN, CONNECTICUT, A CORPORATION OF DELAWARE

SELECTIVE TRIGGER-MECHANISM FOR FIREARMS

Application filed November 22, 1930. Serial No. 497,370.

This invention relates to an improved selective trigger-mechanism primarily designed for double-barrel firearms, but not so limited, and constitutes an improvement upon the mechanism shown and described in my co-pending application, Serial No. 354,088, filed April 10, 1929.

The main object of my present invention is to provide a trigger-mechanism in which one trigger controls more than one barrel, and is characterized by fewness of parts, compactness of organization, certainty of operation, durability in use and convenience of operation.

Another object of my invention is to provide a trigger-mechanism for double-barrel firearms in which the movement of a sear-actuator from its retired into its sear-actuating position is insured by means of a recoil-operated device.

A further object is to provide a selective double-trigger mechanism in which the trigger-pull for firing each of two barrels will be substantially uniform regardless of the particular trigger chosen for operation or of the sequence in which the two triggers are operated.

With the above and other objects in view as will appear from the following, my invention consists in a selective trigger-mechanism for firearms having certain features of construction and combinations and arrangements of parts as will be hereinafter described and particularly recited in the claims.

In the accompanying drawings:

Fig. 1 is a broken view partly in side elevation and partly in vertical longitudinal section of the frame-portion of a double-barrel shotgun embodying my invention, together with the parts associated therewith and showing the parts in the positions due to them when both the firing-mechanisms are in their cocked positions;

Fig. 2 is a view corresponding to Fig 1, but showing the parts in the positions due to them after the forward or right-hand trigger has been pulled, and the right-hand firing-mechanism has been released, but before the rearward draft upon the right-hand trigger has been relaxed;

Fig. 3 is a corresponding view, but showing the parts in the positions due to them after the initial rearward draft upon the right-hand trigger has been relaxed, and with the parts in position in readiness to release the left-hand firing-mechanism;

Fig. 4 is a transverse sectional view taken on the line 4—4 of Fig. 1;

Fig. 5 is a broken view in horizontal section taken on the line 5—5 of Fig. 1;

Fig. 6 is a perspective view of the sear-actuator detached;

Fig. 7 is a similar view of the right-hand trigger detached; and

Fig. 8 is a corresponding view of the left-hand trigger detached.

In the main figures of the accompanying drawings, I have illustrated the firing-mechanisms and associated parts of a double-barrel break-down shotgun, though it will be understood that my invention is applicable to various types of multiple-barrel firearms.

In the embodiment of my invention herein chosen for illustration, I employ a frame 20 formed at its upper rear end with a rearwardly-extending tang 21 and having secured to its under face a trigger-plate 22 between the upper face of the rear end of which latter and the under face of the tang 21, is secured the forward end of a butt-stock 23. A relatively-long screw 24 extends upwardly between the rear end of the trigger-plate 22 aforesaid and the rear end of the tang 21 of the frame 20, and serves to anchor the butt-stock 23 in place in conjunction with a screw 25 extending downwardly through the forward end of the tang 21 and into the upper end of a so-called "lump" 26, formed integral with and upstanding from the trigger-plate 22 already referred to.

The butt-stock 23 above referred to is cut away to clear the mechanism about to be described and is provided near its forward end with a bushing 27 positioned so as to bear at its lower end against the upper face of the lump 26 and at its upper end against the under side of the tang 21 and providing a passageway for the screw 25, already referred to.

Pivots mounted within the frame 20 are

a pair of corresponding right- and left-hand hammers 28 and 29 respectively provided at their forward upper ends with firing-pins 30 and 31, and in their lower rear walls with 5 sear-notches 32 and 33. The said hammers 28 and 29 are also formed at their lower ends, adjacent their sear-notches, respectively, with cam-like heels 32^a and 33^a.

The hammers 28 and 29, just above referred 10 to, are mounted upon a transverse pivot-pin 34, mounted in the frame 20, and are respectively formed with notches 35 and 36 receiving pins 37 and 38 of hammer-operating links 39 and 40, in the usual manner of firearm construction, it being understood that the links 39 and 40 urged forwardly by their springs (not shown) exert a constant effort upon their respective hammers 28 and 29 to swing the upper ends of the same forward into their 20 firing positions.

The sear-notch 32 of the right-hand hammer 28 coacts with the forward end of a horizontally-arranged right-hand sear 41 mounted about midway of its length for oscillation upon a transverse pin 42 in the frame 20.

The rear end of the right-hand sear 41 just above referred to, is provided with an inwardly-projecting finger 43 adapted to be 30 lifted by what I shall for convenience of description, designate as an upwardly-facing "first-stage" firing-ledge 44, formed upon the plate-like body-portion 45 of a right-hand trigger 46.

35 The right-hand trigger 46, just above referred to, is mounted in a right-hand slot 47 complementing a similar left-hand slot 48, both of which are vertical-longitudinal in direction and extend through the trigger- 40 plate 22 upward partway into the rear face of the lump 26. A pivot-pin 49 is mounted in and extends transversely through the said lump 26 and through a perforation 50 extending through the body-portion 45 of the said 45 right-hand trigger near the forward upper edge thereof.

The right-hand trigger 46 is provided with a depending curved finger-piece 51 of usual form and is also formed, just to the rear and 50 slightly below the first-stage firing-ledge 44 thereof, with an upwardly-facing "second-stage" firing-ledge 52 and also with a rearwardly-projecting stop-nose 53 engaging the upper face of the trigger-plate 22, just to the 55 rear of the slot 47 therein for limiting the forward swinging movement of the finger-piece 51.

Complementing the right-hand trigger 46 and located in the left-hand slot 48 in the 60 trigger-plate 22 is a left-hand trigger 54 slightly longer than the right-hand trigger 46 and provided with a curved finger-piece 55 located to the rear of the finger-piece 51 of the said right-hand trigger.

65 The left-hand trigger, above referred to,

is also provided with a plate-like body-portion 56 formed near its forward upper end with a perforation 57 by means of which it is pivotally mounted upon the pivot-pin 49 already referred to. The trigger 54 under discussion is also provided with a rearwardly-extending stop-nose 58 engaging the upper face of the trigger-plate 22, just to the rear of the slot 48 therein and is further provided, like the right-hand trigger already described, with an upwardly-facing second-stage firing-ledge 59 and a similarly-facing first-stage firing-ledge 60.

The first-stage firing-ledge 60 of the left-hand trigger, just above referred to, is adapted to engage the under-face of a sear-finger 61 inwardly offsetting from a left-hand sear 62 corresponding to the right-hand sear 41, already described, and like the same mounted upon the transverse pivot-pin 42 already referred to. The forward end of the left-hand sear 62 coacts with the sear-notch 33 of the left-hand hammer 29 and with the cam-like heel 33^a thereof as will hereinafter appear.

The right-hand trigger 46 and the left-hand trigger 54 are so formed that the finger-piece 55 of the latter is located substantially in line with and directly back of the finger-piece 51 of the said right-hand trigger, with sufficient space between them for the ready insertion of the trigger finger of the user of the arm.

The lump 26 of the trigger-plate 22 is formed with a central longitudinal passage 63 intersecting the slots 47 and 48 therein and extending from front to rear therethrough for the accommodation of a plate-like sear-actuator 64 which is provided about midway of its length with a transverse clearance-slot 65, through which the pivot-pin 49 passes, as clearly shown in Fig. 5 of the drawings.

By means of the slot 65 and the pivot-pin 49, the sear-actuator 64 just above referred to, is mounted in the lump 26 with capacity for longitudinal reciprocation, rocking movement, and a limited bodily vertical movement, and is widened out near its forward end where it is provided in its under-face with a downwardly- and rearwardly-inclined spring-pocket 66 receiving the upper end of a helical spring 67 encircling a plunger 68. The lower end of the said plunger is seated in a conical seat 69 in the trigger-plate 22, just forward of the slots 47 and 48 therein. The said spring 67 exerts a constant effort to move the sear-actuator 64 bodily forward and to rock the forward end thereof upward.

The upper rear end of the sear-actuator 64 is formed with a stop-projection 70 and at its lower rear end with oppositely-extending laterally-offsetting right- and left-hand sear-actuating lugs 71 and 72 respectively.

The right-hand sear-actuating lug 71 of the sear-actuator 64 overlies the second-stage

firing-ledge 52 of the right-hand trigger and is adapted to move beneath the finger 43 of the right-hand sear 41 for lifting the same under the urge of the left-hand trigger 54, to discharge the right-hand barrel (not shown) of the arm, as will hereinafter appear.

The left-hand sear-actuating lug 72 of the sear-actuator 64 complements the right-hand lug 71 thereof and projects from the opposite face thereof in position to overlie the second-stage firing-ledge 59 of the left-hand trigger 54, and is adapted to move beneath the finger 61 of the left-hand sear 62 for lifting the same under the urge of the right-hand trigger 46 to discharge the left-hand barrel (not shown), as will hereinafter appear.

The upper edge of the sear-actuator 64 near its forward end, is provided with a forwardly-facing slightly-inclined latching-shoulder 75 adapted to coact with a latching-bar 76 mounted in a transverse rectangular groove 77 in the front face of the lump 26 in position to extend across the longitudinal passage 63 in the said lump, through which the sear-actuator 64 extends. The said latching-bar 76 is secured in place by swaging the metal of the slot 77 over the edge of its opposite ends, though if desired, it may be made integral with the said lump 26.

The rear-under face 78 of the sear-actuator 64 is of arcuate form and is adapted to coact with a pivotal inertia-weight 79 as will hereinafter appear, which is mounted upon a transverse pin 80 in the trigger-plate 22 and is normally held in its rearward or retired position by a plunger 81 engaging the upper surface of the said trigger-plate adjacent the pivot-pin 80 and reciprocating in an inclined bore 82 in the said inertia-weight, and urged outward by a helical spring 83 also located in the said bore 82 and encircling the reduced upper end of the said plunger 81.

The stop-projection 70 of the sear-actuator 64 is adapted to coact on occasion with the under-face of a reciprocating safety-rod 84 and also to enter a vertical longitudinal clearance-groove 85 formed in the under-face thereof. The forward portion of the safety-rod 84 is of cylindrical form and reciprocates in a longitudinal guide-passage 86 formed in the lump 26. The extreme forward end 87 of the said safety-rod 84 is reduced in diameter and externally threaded to fit into a threaded bore 88 in a removable extension-piece 89.

The rear end of the safety-rod 84 is pivotally secured, by means of a pin 90, to a substantially vertical safety-lever 91 mounted for oscillation forward and back upon a pin 92 extending transversely through the trigger-plate 22 near the rear end thereof.

The rear end of the inertia-weight 79 is formed with a clearance-notch 93 for the

clearance of the lever 91, the upper end of which latter is entered into a downwardly-opening notch 94, formed in a safety-slide 95 sliding longitudinally upon the upper face of the tang 21 of the frame 20, in the usual manner of safety-mechanisms. A detent-spring 96 is carried by the said slide and is formed at its forward end with an upwardly-extending hump 97 adapted to enter either one of two detent-notches 98 and 99 to yieldingly retain the said slide in either one of its two positions.

The forward end of the removable extension-piece 89 of the safety-rod 84 is adapted to be engaged by the rear face of a locking-bolt 100 in the usual manner of breakdown firearms. The operation and construction of locking-mechanisms is so well understood in the art that it is believed that no further description is required other than to say that the said locking-bolt 100 is retracted by a finger 101 depending from a head 102 mounted upon the lower end of the shank 103 of a laterally-swinging top-lever 104, which effects the unlocking of the piece for the breakdown action, in the usual manner of breakdown firearms.

The finger-pieces 51 and 55 of the respective right- and left-hand triggers 46 and 54 are guarded in the usual manner by a trigger-bow 105 mounted upon the under-face of the trigger-plate 22, as clearly shown in Figs. 1, 2 and 3 inclusive.

Coming now to the operation of my improved trigger-mechanism, let it be supposed that the gun is fully cocked so that the parts occupy the positions in which they are shown in Figs. 1, 4 and 5 of the drawings.

By reference to the figures just above referred to, it will be seen that both hammers are in their cocked positions and that the sear-actuator 64 is held in its rearmost position against the forward urge of the spring 67, by the engagement of its latching-shoulder 75 with the rear face of the latching-bar 76 so that the sear-actuating lugs 71 and 72 are to the rear of the respective sear-fingers 43 and 61. In other words, the sear-actuator 64 is in its retired or inoperative position and the bottom of the slot 65 rests against the under-side of the pin 49.

It will also be noted by reference to the figures referred to that the finger 43 of the right-hand sear 41 overlies the first-stage firing-ledge 44 of the right-hand trigger 46, and the finger 61 of the left-hand sear 62 overlies the first-stage firing-ledge 60 of the left-hand trigger 54.

With the parts in their fully-cocked positions, as above described, let it be supposed that the user of the arm desires to fire the right-hand barrel of the gun first. With the above object in view, the user of the arm will exert a rearward draft upon the finger-piece 51 of the right-hand trigger 46 and cause the

latter to swing upon the pivot-pin 49 to bring its first-stage firing-ledge 44 into operative engagement with the finger 43 of the right-hand sear 41, and thus swing the latter so as to disengage its forward end from the sear-notch 32 in the right-hand hammer 28. The right-hand hammer will thus be permitted to swing forward in the usual manner of firearms to fire the cartridge in the right-hand barrel (not shown).

In swinging forward to fire a cartridge, as above described, the right-hand hammer 28 will act through its cam-like heel 32^a to depress the forward end of the right-hand sear 41 and thus lift the finger 43 thereof into a clearance position, as shown in Figs. 2 and 3.

The swinging movement of the right-hand trigger as above described, will first disengage the forward end of the right-hand sear 41 from the sear-notch 32 of the right-hand hammer 28 so as to permit the latter to fire the right-hand barrel, and will also act through its second-stage firing-ledge 52 to rock the sear-actuator 64 about the pin 49 as a fulcrum-point, to disengage the latching-shoulder 75 thereof from the latching-bar 76 subsequently to the release of the hammer 28 with the effect of permitting the said sear-actuator to move bodily forward under the urge of the spring 67 until the forward face of its left-hand lug 72 engages with the rear face of the finger 61 of the left-hand sear 62. The parts will have now assumed the positions in which they are shown in Fig. 2, in which the rearward draft upon the right-hand trigger 46 has not as yet been relaxed by the user of the arm.

When the right-hand barrel is fired, as above described, the recoil of the firearm will cause the pivotal inertia-weight 79 to swing forward into the position in which it is shown in Fig. 2, in which position its periphery is interposed beneath the arcuate rear surface 78 of the sear-actuator 64, thus temporarily blocking the downward movement of the rear end thereof. When the counter-recoil takes place, the said inertia-weight will be returned, by the combined action of its spring 83 and the counter-recoil, to the position indicated in Figs. 1 and 3.

The action of the inertia-weight just above described, serves at this time to prevent the downward movement of the rear end of the sear-actuator 64 and hence its further forward movement into position to bring its lug 72 beneath the finger 61 of the left-hand sear 62 for actuating the same as an incident to the recoil of the arm. From the foregoing it will be seen that the forward movement of the inertia-weight forestalls an involuntary second movement of the right-hand trigger and the consequent unintentional firing of the second barrel as a result of the counter-recoil.

The right-hand barrel having been fired,

as above described, and the recoil and counter-recoil having expended their forces, the user deliverably relaxes the rearward draft upon the finger-piece 51 of the right-hand trigger 46 to permit the said finger-piece to swing forward under the urge of the sear-actuator 64 from the position in which it is shown by full lines in Fig. 2 to the position in which it is shown by broken lines in the same figure. This forward or return movement of the right-hand trigger permits the rear end of the sear-actuator 64 to swing downward sufficiently to permit its left-hand sear-actuating lug 72 to ride under the finger 61 of the left-hand sear 62.

The parts will now occupy the positions in which they are shown in Fig. 3, in readiness to release the left-hand hammer for firing the left-hand barrel (not shown); which may now be effected by a pull upon either trigger.

If the right-hand trigger which has just been operated, is chosen to also effect the firing of the left-hand barrel, a second rearward draft thereupon will cause the second-stage firing-ledge 52 thereof to engage the under-face of the right-hand lug 71 of the sear-actuator, with the effect of lifting the rear end of the latter and causing the upper face of its left-hand lug 72 to engage and lift the finger 61 of the left-hand sear 62, which latter will be swung so as to disengage its forward end from the sear-notch 33 in the left-hand hammer 29 so that the same will swing forward and fire the left-hand barrel (not shown). The inertia-weight 79 will operate in the same manner under the action of the recoil and counter-recoil of the firearm as previously described.

If the user of the arm should have preferred to fire the left-hand barrel by means of the left-hand trigger instead of by means of the right-hand trigger, as described, assuming the parts to be in the positions shown in Fig. 3, a rearward draft upon the left-hand trigger would cause the first-stage firing-ledge 60 of the said left-hand trigger to act directly upon the finger 61 of the left-hand sear 62 to rock the latter and thus release the left-hand hammer 29.

As has been herein pointed out when starting with the gun fully cocked, the firing of the first barrel, whether right or left, occurs before the appropriate trigger has been pulled sufficiently for effecting the disengagement of the latching-shoulder 75 of the sear-actuator 64 from the latching-bar 76 so as to permit the sear-actuator to move forward toward its sear-actuating position.

Now it may be here pointed out that occasionally a marksman having a very slow "trigger pull" will sometimes fail to continue to pull upon the chosen trigger sufficiently far to unlatch the sear-actuator, owing largely to the effect of the recoil in tending to move the trigger away from his finger.

Ordinarily when this condition occurs and the sear-actuator has not been unlatched, a second intentional pull upon the same trigger will fail to discharge the other barrel of the 5 arm, due to the fact that the sear-actuator has failed to move into its sear-actuating position.

To guard against the undesirable effects of an incomplete trigger-pull, as outlined 10 above, the inertia-weight 79 and the rear end of the sear-actuator 64 are so arranged and proportioned that when the first barrel is fired, the resulting recoil will automatically cause the rounded upper front corner of the 15 said inertia-weight to strike the rounded rear end of the sear-actuator to cam the latter upward sufficiently to insure the disengagement of the latching-shoulder 75 from the latching-bar 76, in the event that the user 20 of the arm has failed to accomplish this unlatching by a full and complete pull upon the trigger.

When the user wishes to reload the arm, this may be accomplished by swinging the 25 top-lever 104 laterally to retract the locking-bolt 100 and "break" the piece, thus effecting the cocking of both of the hammers 28 and 29, all in the well-known manner of breakdown firearms.

When the locking-bolt 100 is retracted, as just above described, it will engage the front face of the extension-piece 89 of the safety-rod 84 and force the latter rearward with the effect of also sliding the safety-slide 95 30 rearward and with the further effect of moving the clearance-slot 85 in the safety-rod 84 out of registration with the stop-projection 70 of the sear-actuator 64 so that neither trigger can be swung for firing the gun until 35 the safety-rod has again been manually restored to the position in which it is shown in the drawings, by means of its slide 95.

From the foregoing, it will be seen that the safety-mechanism of the gun is automatically 40 thrown into a safety position as an incident to the breakdown action of the arm. If this automatic safety action is not desired, it may be readily eliminated as a feature of the gun by the removal of the extension-piece 89 45 of the safety-slide 84.

When the user is ready to fire the gun, he manually moves the safety-rod 84 forward by means of the safety-slide 95 thereby bringing the clearance-slot 85 into registration with 50 the stop-projection 70 of the sear-actuator, and the safety-mechanism will remain in this inoperative position until intentionally moved therefrom.

In the foregoing description of operation, 55 I have described my improved trigger-mechanism as employed to release the hammers 28 and 29 in the order "right-left," but it will be seen that if the user of the arm chooses to reverse the firing order, namely, to "left-right," he has but to first operate the left-

hand trigger 54 to fire the left-hand barrel and subsequently he may fire the remaining barrel by means of either trigger.

I wish to call particular attention to the fact that in the construction shown, the trigger pull required for firing either barrel is substantially uniform. This marked refinement and advantage is largely due to the fact that the cam-like heels 32^a and 33^a of the respective hammers serve to hold the complementary sear with which each cooperates in such position as not to impose additional strain upon either trigger when the second barrel is fired.

It will be understood by those skilled in the art that my invention may assume varied physical forms without departing from my inventive concept and I, therefore, do not limit myself to the specific embodiment herein chosen for illustration, but only as indicated in the appended claims.

I claim:

1. In a selective double-trigger mechanism for double-barrel firearms, the combination with a pair of firing-mechanisms including the respective sears thereof; of a shiftable sear-actuator adapted to directly operate the said sears and having a retired and a sear-actuating position; a pair of triggers each adapted to directly actuate its complementary sear independently of the said sear-actuator for releasing one firing-mechanism and each adapted to move the said sear-actuator to cause the same to release the other of the said firing-mechanisms through the intermediary of the sear thereof; spring-means normally urging the said sear-actuator into position to directly actuate one of said sears; and latching-means for releasably holding the said sear-actuator in its retired position and releasable by a movement of the said sear-actuator itself to permit the same to move into its sear-actuating position.

2. In a selective double-trigger mechanism for double-barrel firearms, the combination with a pair of firing-mechanisms including the respective sears thereof; of a sear-actuator adapted to directly operate the said sears and having a retired and a sear-actuating position; a pair of triggers each adapted to directly actuate its complementary sear independently of the said sear-actuator for releasing one firing-mechanism and each adapted to rock the said sear-actuator to cause the same to release the other of the said firing-mechanisms by the direct engagement of the said sear-actuator with the sear thereof; spring-means normally urging the said sear-actuator into its sear-actuating position; and latching-means for releasably holding the said sear-actuator in its retired position and releasable by a rocking movement of the said sear-actuator itself to permit the same to move into its sear-actuating position.

3. In a selective double-trigger mechanism

for double-barrel firearms, the combination with a pair of firing-mechanisms including the respective sears thereof; of a shiftable sear-actuator normally pivoted between its ends so as to have two oppositely-extending arms and adapted to directly operate the said sears and having a retired and a sear-actuating position; a pair of triggers each adapted to directly actuate its complementary sear independently of the said sear-actuator for releasing one firing-mechanism and each adapted to move the said sear-actuator to cause the same to release the other of the said firing-mechanisms through the intermediary of the sear thereof; spring-means normally urging the said sear-actuator into its sear-actuating position; a latching-abutment mounted in the gun-structure; and a complementary latching-abutment carried by the arm of the said sear-actuator remote from that arm thereof which is engaged by the said triggers, and adapted for engagement with the first-mentioned latching-abutment for holding the said sear-actuator in its retired position and disengageable by a movement of the said sear-actuator itself to permit the same to move into its sear-actuating position.

4. In a selective double-trigger mechanism for double-barrel firearms, the combination with a pair of firing-mechanisms including the respective sears thereof; of a sear-actuator normally pivoted between its ends so as to have two oppositely-extending arms and adapted to directly operate the said sears and having a retired and a sear-actuating position; a pair of triggers each adapted to directly actuate its complementary sear independently of the said sear-actuator for releasing one firing-mechanism and each adapted to rock the said sear-actuator to cause the same to release the other of the said firing-mechanisms through the intermediary of the sear thereof; spring-means normally urging the said sear-actuator into its sear actuating position; a latching-abutment mounted in the gun-structure; and a complementary latching-abutment carried by the arm of the said sear-actuator remote from that arm thereof which is engaged by the said triggers, and adapted for engagement with the first-mentioned latching-abutment for holding the said sear-actuator in its retired position and disengageable by a rocking movement of the said sear-actuator itself to permit the same to move into its sear-actuating position.

5. In a selective double-trigger mechanism for double-barrel firearms, the combination with a pair of firing-mechanisms including the respective sears thereof; of a sear-actuator loosely mounted between the ends upon a transverse pivot with capacity for both rocking and reciprocating movement and adapted to directly operate the said sears and having a retired and a sear-actuating position; a pair of triggers each adapted to directly

actuate its complementary sear independently of the said sear-actuator for releasing one firing-mechanism and each adapted to rock the said sear-actuator to cause the same to release the other of the said firing-mechanisms by the direct engagement of the said sear-actuator with the sear thereof; spring-means normally urging the said sear-actuator into its sear-actuating position; and latching-means for releasably holding the said sear-actuator in its retired position and releasable by a rocking movement of the said sear-actuator itself to permit the same to move into its sear-actuating position.

6. In a selective double-trigger mechanism for double-barrel firearms, the combination with a pair of firing-mechanisms including the respective sears thereof; of a reciprocating and rocking sear-actuator normally pivoted between its ends and adapted to directly operate the said sears and having a retired and a sear-actuating position; a pair of triggers respectively located upon the opposite sides of the said sear-actuator and each adapted to directly actuate its complementary sear independently of the said sear-actuator for releasing one firing-mechanism and each adapted to move the said sear-actuator to cause the same to release the other of the said firing-mechanisms by the direct engagement of the said sear-actuator with the sear thereof; spring-means normally urging the said sear-actuator into its sear-actuating position; and latching-means for releasably holding the said sear-actuator in its retired position and releasable by a rocking movement of the said sear-actuator itself to permit the same to move into its sear-actuating position.

7. In a selective double-trigger mechanism for double-barrel firearms, the combination with a pair of firing-mechanisms including the respective sears thereof; of a reciprocating and rocking sear-actuator normally pivoted between its ends so as to have two oppositely-extending arms and adapted to directly operate the said sears and having a retired and a sear-actuating position; a pair of triggers respectively located upon the opposite sides of the said sear-actuator and each adapted to directly actuate its complementary sear independently of the said sear-actuator for releasing one firing-mechanism and each adapted to rock the said sear-actuator to cause the same to release the other of the said firing-mechanisms through the intermediary of the sear thereof; spring-means normally urging the said sear-actuator into its sear-actuating position; a latching-abutment mounted in the gun-structure; and a complementary latching-abutment carried by the arm of the said sear-actuator remote from that arm thereof which is engaged by the said triggers, and adapted for engagement with the first-mentioned latching-abut-

ment for holding the said sear-actuator in its retired position and disengageable by a rocking movement of the said sear-actuator itself to permit the same to move into its 5 sear-actuating position.

8. In a selective double-trigger mechanism for double-barrel firearms, the combination with a pair of firing-mechanisms including the respective sears thereof; of a shiftable 10 sear-actuator adapted to directly operate the said sears and having a retired and a sear-actuating position; a pair of triggers each adapted to directly actuate its complementary sear independently of the said sear-actuator for releasing one firing-mechanism 15 and each adapted to move the said sear-actuator to cause the same to release the other of the said firing-mechanisms by direct engagement with the sear thereof; spring- 20 means normally urging the said sear-actuator into its sear-actuating position; latching-means for releasably holding the said sear-actuator in its retired position and releasable by a movement of the said sear- 25 actuator itself to permit the same to move into its sear-actuating position; and a recoil-operated safety device physically distinct from and adapted to directly engage the said sear-actuator to momentarily prevent the 30 same from moving into its sear-actuating position until the recoil and counter-recoil have expended their forces.

9. In a selective double-trigger mechanism for double-barrel firearms, the combination with a pair of firing-mechanisms including the respective sears thereof; of a reciprocating and rocking sear-actuator adapted to directly operate the said sears and having a retired and a sear-actuating position; a pair 35 of triggers each adapted to directly actuate its complementary sear independently of the said sear-actuator for releasing one firing-mechanism and each adapted to rock the said sear-actuator to cause the same to release the other of the said firing-mechanisms by direct engagement with the sear thereof; spring-means normally urging the said sear-actuator into its sear-actuating position; 40 latching-means for releasably holding the said sear-actuator in its retired position and releasable by a rocking movement of the said sear-actuator itself to permit the same to move into its sear-actuating position; and a recoil-operated safety device physically distinct from and adapted to directly engage the said sear-actuator to momentarily prevent the same from moving into its sear-actuating position until the recoil and counter-recoil have expended their forces.

10. In a selective double-trigger mechanism for multiple-barrel firearms, the combination with a pair of sears; of a pair of triggers, each adapted to independently operate its complementary sear; a sear-actuator 65 mounted for both reciprocating and rocking

movements and having a retired position and a sear-actuating position, and adapted when in its active position to operate either of the said sears and movable for the latter purpose by either one of the two said triggers 70 without moving the other trigger; spring-means normally urging the said sear-actuator into its sear-actuating position; and latching-means for holding the said sear-actuator in its retired position and releasable by a rocking movement of the latter which may be effected by either of said triggers for permitting the said spring-means to move the said sear-actuator into its sear-actuating position. 80

11. In a selective double-trigger mechanism for double-barrel firearms, the combination with a pair of firing-mechanisms including the respective sears thereof; of a pair of triggers adapted to effect the operation of the said sears; a shiftable sear-actuator adapted to operate the said sears and having a retired and a sear-actuating position and movable into its latter position in response to a movement of either of the said triggers; and an automatic recoil-operated member constructed and arranged to effect the movement of the said sear-actuator into its sear-actuating position in response to the recoil of the firearm, should the user fail to 95 manually effect the same by means of one of the said triggers.

12. In a selective double-trigger mechanism for double-barrel firearms, the combination with a pair of firing-mechanisms including the respective sears thereof; of a pair 100 of triggers adapted to effect the operation of the said sears; a shiftable sear-actuator adapted to operate the said sears and having a retired and a sear-actuating position; spring-means normally urging the said sear-actuator into its sear-actuating position; latching-means for releasably holding the said sear-actuator in its retired position and releasable by a firing movement of either 105 of the said triggers; and an automatic recoil-operated sear-actuator-releasing member constructed and arranged to unlatch the said latching-means in response to the recoil of the firearm, should the user fail to manually 110 effect the same by means of one of the said triggers. 115

13. In a selective double-trigger mechanism for double-barrel firearms, the combination with a pair of firing-mechanisms including the respective sears thereof; of a pair 120 of triggers adapted to effect the operation of the said sears; a reciprocating-and-rocking sear-actuator adapted to operate the said sears and having a retired and a sear-actuating position; spring-means normally urging the said sear-actuator into its sear-actuating position; latching-means for releasably holding the said sear-actuator in its retired position and releasable by a rocking movement of 125

- the said sear-actuator itself under the urge of either of the said triggers; and an automatic recoil-operated sear-actuator-releasing member constructed and arranged to rock the
5 said sear-actuator to unlatch the same in response to the recoil of the firearm, should the user fail to manually unlatch the said sear-actuator by means of one of the said triggers.
- 10 14. In a selective double-trigger mechanism for double-barrel firearms, the combination with a pair of firing-mechanisms including the respective sears thereof; of a pair of triggers adapted to effect the operation of
15 the said sears; a reciprocating-and-rocking sear-actuator adapted to operate the said sears and having a retired and a sear-actuating position; spring-means normally urging the said sear-actuator into its sear-actuating
20 position; a latching-abutment mounted in the gun-structure; a complementary latching-abutment carried by the said sear-actuator for engagement with the first-mentioned latching-abutment for holding the said sear-
25 actuator in its retired position and disengagable by a rocking movement of the said sear-actuator itself under the urge of either of the said triggers; and an automatic recoil-operated sear-actuator-releasing member con-
30 structed and arranged to rock the said sear-actuator to unlatch the same in response to the recoil of the firearm, should the user fail to manually unlatch the said sear-actuator by means of one of the said triggers.
- 35 In testimony whereof, I have signed this specification.

LOUIS STIENNON.
